CARBURETER.

966,381.

Specification of Letters Patent.

Patented Aug. 2, 1910.

Application filed July 28, 1909. Serial No. 510,107

To all whom it may concern:

Be it known that I, EVERETT P. BROOKS, a citizen of the United States, residing at Cincinnati, in the county of Hamilton and 5 State of Ohio, have invented certain new and useful Improvements in Carbureters; and I do declare the following to be a full, clear, and exact description of the invention, reference being had to the accompanying 10 drawings, and to the letters and figures of reference marked thereon, which form a part of this specification.

This invention relates to carbureters of the type that are used in connection with 15 explosion engines, the invention having reference particularly to a reservoir and to the apparatus for admitting and controlling the air to be carbureted, and to apparatus for feeding the gasoline or similar hydro- 20 carbon from the reservoir to produce the explosive mixture for the engines.

Objects of the invention are to provide an improved carbureter of the above-mentioned character that will be adapted to be constructed compactly, and at relatively small expense, and be adapted to be operated reliably, and with the highest efficiency under varied conditions required, and be durable and economical in use.

30 The invention consists in an improved carbureter comprising a feed reservoir having vaporizing and mixing apparatus therein of novel construction, and an air inlet valve of novel construction and arrangement mounted on the reservoir, the reservoir having a duct therein through which the explosive mixture is conducted from the vaporizing apparatus out through the reservoir; and the invention consists further in the 35 novel parts, and combinations and arrangements of parts, as hereinafter particularly described and then defined in the appended claims.

45 Referring to the drawings, Figure 1 is a top plan of the improved carbureter; Fig. 2, a vertical central sectional view thereof; Fig. 3, a horizontal sectional view on the plane of the line A A in Fig. 2; Fig. 4, a fragmentary sectional view on the plane of 50 the line B B in Fig. 2 looking upward; Fig. 5, a fragmentary sectional view on the plane of the line C C in Fig. 2; Fig. 6, a vertical central sectional view omitting some of the parts of the carbureter on a plane at right

angles to the plane of the section on which 55 Fig. 2 is taken; and Fig. 7, a perspective view of one of the vaporizing devices of the carbureter.

In the drawings like parts or features of construction are indicated by similar reference characters throughout the several figures.

As preferably constructed the invention comprises a reservoir having a side wall 1 and a bottom 1' in which is an aperture 1'', the wall 1 having a horizontal tube 2 connected thereto and extending inward, the tube having a vertical branch 3 that has a flaring portion 4 from which extends a cylindrical portion 5 that terminates approximately at the plane of the top of the wall 1, the reservoir having a cover 6 that is seated on the wall 1 and also on the top of the cylindrical portion 5 of the tube which forms a vaporizing tube and conduit 75 through the reservoir. The cover 6 has a central aperture 7 therein of somewhat less diameter than that of the cylindrical portion 5, the latter having internal screw-threads 8 therein. A tube 2' extends from 80 the wall 1 outward in alignment with the horizontal tube 2 and has a valve-body 9 thereon from which extends a tube 10 adapted to be connected with an engine or a pipe, the valve-body having a valve-plug 11 85 therein through which is a transverse port 12 for regulating the flow of the explosive mixture from the vaporizing apparatus, the plug having an operating handle 11' thereon. The tube 2 has an aperture 2'' in 90 the lower portion thereof, in which is secured the lower end of a vertical feed tube 13 having a vaporizing feed-head 14 on its upper end, the feed-head having a conical top 14' in the apex of which is a relatively 95 small aperture 15 for the escape of gasoline. The top of the feed-head has an annular trough that extends along the periphery at the base thereof which serves to assist in vaporizing the gasoline and in carbureting 100 the air, and it serves also to catch and retain a small quantity of gasoline that may escape from the aperture 15 after the engine has stopped, to be utilized in case the engine is again started before the gasoline evaporates. A bushing 17 is inserted in the aperture 1'', and a valve stem 18 is screwed into the bushing and extends up through the 105

feed tube 13 and has a feed-valve 19 on its upper end to coöperate with the inner side of the feed-head 14 for regulating the flow of gasoline from the aperture 15, the lower end of the valve stem having an operating stem 20 thereon provided with a packing-nut 21 and a packing 22 connected with the bushing 17 that is adapted to serve as a packing-box.

10 An inlet tube 23 extends from the bottom 1' upward near the inner side of the wall 1 and has an outlet opening 24 in its side, a tube 25 extending from the outer side of the bottom in alignment with the tube 23 and adapted to have a supply-pipe connected thereto, the interior of the tube 25 having a valve-seat 25' therein. A valve-stem 26 is inserted in the tubes and has an inlet valve 27 on its lower end to operate on the seat 25', the upper end of the stem 26 preferably having a relatively large head 28 thereon to serve as a weight for seating the valve. A bracket 29 is attached to the inner side of the wall 1 by a securing device 30, and a lever 31 is connected to the bracket by a pivot 32 and is connected also to the head 28 by a pivot 33, the lever having two arms 34 and 34' that extend in opposite directions toward the wall 1 and partially about the upright portions of the vaporizing tube to the under side of an annular float 35 that extends about the cylindrical portion 5, the arrangement being such that when the float rises on the liquid in the reservoir to the desired height the valve 27 will close automatically, and when the float descends the valve will open and admit gasoline which will be discharged through the aperture 24 into the reservoir.

40 The feed-head 14 is situated in the cylindrical portion 5, or a suitable distance above the wall of the flaring portion 4, so that the gasoline will be forced from the conical top against the wall of the tube. The cover 6 is provided with a guide case 36 that is inserted therein above a portion of the float and has a plunger 37 guided therein, a spring 38 being mounted on the bottom of the case and having its upper end in contact with a collar 39 on the plunger, the latter having a head 40 on its lower end extending from the bottom of the case downward, so that when it is desired to admit somewhat more than the usual quantity of gasoline 55 into the reservoir the plunger may be pushed down onto the float in order to lift the valve 27 from its seat.

A tube 41 comprising an adjustable air-inlet part of the vaporizing tube is inserted 30 through the aperture 7 in the cover 6 and has a bell-shaped lower end 42 which has external screw-threads 43 theron that engage the screw-threads 8, whereby the tube is adjustably connected to the inner side of 65 the cylindrical portion 5, so that the bell-

shaped end portion 42 may be adjusted relatively to the feed-head 14. A lock-nut 44 is screwed onto the exterior of the tube 41 and is seated upon the cover 6 for retaining the cover on the reservoir. A valve-case 45 is secured to the upper end of the tube 41, being above the cover 6, the case having a relatively small lower end 46 whereby it is connected to the tube. The valve-case has an inwardly extending flange 75 47 on its upper end, in which are a suitable number of air inlet openings 48, the flange having a valve-seat 49 at its under side and having also an outward extending tubular flange 50 around which extends a 80 plate 51 that is seated on the flange 47 and has air inlet openings 52 therein that normally register with the openings 48, so that the latter may be partially closed by adjusting the plate 51 rotatively, a nut 53 being 85 connected to the flange 50 for securely holding the plate 51 when adjusted. The upright flange 50 which comprises an air inlet tube has a bridge 54 therein in which is mounted a screw 55 provided with a lock-nut 56 that is normally seated on the bridge, the screw extending downward and having a guide-stem 57 on its lower end, on which is mounted an air inlet valve 58 to coöperate with the seat 49, the lower end of the 90 guide stem having a spring-seat 59 thereon supporting a spring 60 that engages the under side of the valve for normally holding it to its seat.

The tube 2' preferably has a drip-hole 61 in the lower portion of the wall thereof for the escape of any overflow of gasoline from the feed-head that may occur through accident or carelessness, so that overcharging of the engine may be avoided.

In practical use, when the engine is being started and before vacuum-producing suction occurs air is admitted through the openings 48 and passes through the valve-case and the tube 41 and out through the port 12 of the regulating valve 11, being carbureted in its passage by the hydro-carbon liquid that escapes from the feed-head 14, and after sufficient suction is produced to unseat the valve 58 the larger volume 1 required will be admitted thereby and will be drawn forcibly against the conical feed-head and thence against the wall of the flaring portion 4 of the vaporizing tube, being thoroughly carbureted by the hydro-carbon liquid. Other results of operation will be readily understood from the foregoing detailed description of the construction of the carburetor.

Having thus described the invention, what is claimed as new, is—

1. A carburetor including a vertical vaporizing tube, and a feed-tube in the vaporizing tube and having a hollow combined feed-head and vaporizing head thereon that

has a conical upper end and an outlet opening in the apex thereof, the conical end having a trough extending about the base thereof.

5. A carbureter including a vertical vaporizing tube having an enlarged portion, a feed-tube extending into the enlarged portion of the vaporizing tube and having a hollow combined feed-head and vaporizing head thereon that has a conical upper end and an outlet opening in the apex thereof, the conical end having a trough extending about the base thereof, and a feed-valve in the feed-head and vaporizing-head opposite the opening.

3. A carbureter including a vaporizing tube comprising a vertical portion, a flared portion extending from the vertical portion, and a cylindrical portion extending from 20 the flared portion, the cylindrical portion having screw-threads therein, and a tube having a bell-shaped end that has screw-threads thereon engaging the screw-threads of the cylindrical portion, the bell-shaped 25 end being opposite the flaring portion; and a feed-tube extending into the flared portion and having a relatively large hollow head thereon that has a conical end disposed opposite to the bell-shaped end, the head 30 having an aperture therein.

4. A carbureter including an air-inlet tube, a valve-case on the tube, a head on the valve-case having a central aperture therein and also a plurality of relatively 35 small apertures in a circle about the central aperture, the head having a valve-seat on the inner side thereof and also a flange on the outer side thereof extending about the central aperture, said flange having external 40 screw-threads thereon, an annular plate extending about the flange on the head and having a plurality of apertures therein to register with the small apertures in the head, a nut on the flange engaging the screw-45 threads and the plate, and a valve spring-pressed against the valve-seat.

5. A carbureter including a reservoir, a vaporizing tube extending from the side of the reservoir horizontally and thence 50 vertically therein, the upper portion of the tube being larger diametrically than the lower portion thereof, an annular cover seated upon the reservoir and also upon the tube, a feeding and vaporizing head mounted 55 in the larger portion of the tube, an air-inlet and vaporizing tube part extending through the cover and secured in the larger portion of the vaporizing tube, a valve-case on the

air-inlet tube part and having apertures 60 therein, an air-inlet valve mounted in the valve-case, a nut on the air-inlet tube part seated on the cover, and an inlet to admit liquid to the reservoir.

6. A carbureter including a reservoir, a vaporizing tube in the reservoir comprising 65 a flared portion and a cylindrical portion extending from the flared portion, the cylindrical portion having screw-threads therein, an annular cover seated on the reservoir and also on the cylindrical portion of the tube, 70 and an adjustable air-inlet and vaporizing tube part extending through the annular cover and having a bell-shaped end that has screw-threads thereon engaging the screw-threads of the cylindrical portion, the adjustable tube part having screw-threads on the main portion thereof, the bell-shaped end being opposite to the flaring portion; a nut on the main portion of the adjustable tube part engaging the screw-threads thereof and seated on the annular cover, and a feed-tube extending into the flaring portion of the tube and having a relatively large 75 hollow head thereon that has a conical end disposed opposite to the bell-shaped end of 80 the adjustable tube part, the head having an aperture therein.

7. A carbureter including a reservoir, a vaporizing tube extending from the side of the reservoir horizontally and thence vertically therein, the upper portion of the tube being larger diametrically than the lower portion thereof, an annular cover seated upon the reservoir and also upon the tube, a feeding and vaporizing head mounted in 90 the larger portion of the tube part, an air-inlet and vaporizing tube extending through the cover and secured in the larger portion of the vaporizing tube, a valve-case on the said air-inlet tube part, an air-inlet valve mounted in the valve-case, a nut on the said air-inlet tube part seated on the cover, a lever pivoted in the reservoir and having two arms that extend at opposite sides of the vertical portion of the vaporizing tube, an inlet valve in the reservoir connected with the lever, and an annular float in the reservoir extending about said larger portion of 95 the vaporizing tube upon the two arms of the lever.

In testimony whereof, I affix my signature in presence of two witnesses.

EVERT P. BROOKS.
